TEMPERATURE CONTROL FOR INTERNAL-COMBUSTION MOTORS.

Application filed March 30, 1925. Serial No. 19,399.

This invention relates to means for heating the explosive mixture that is delivered to an internal combustion motor in order that the explosive mixture may be expanded and 5 made more effective; and it is furthermore an object of the invention to produce a device of the character indicated which will operate prior to the starting of the internal combustion motor in order that the said device will 10 prove effective in cold weather and expedite the starting of internal combustion motors in such weather.

It is a further object of this invention to 15 produce means for heating the interior of an automobile body, by delivering heat through a heating register or the like, in order that the interior of the said automobile may be kept at a proper temperature for the comfort of the occupants.

20 It is a still further object of this invention to produce means for heating the interior of an internal combustion motor in order that oil or lubricant in such motor may have a higher temperature than it would ordinarily 25 have, a condition which will insure proper action of the lubricant and preserve the operating parts of the mechanism.

It is a still further object of this invention 30 to produce a combined heater and ventilator in order that the interior of the automobile, or the interior of the motor, may be supplied with air under forced circulation during the heated terms of the year, thereby making it possible with the use of one system to either 35 heat or cool the air in the automobile or in the interior of the motor.

With the foregoing and other objects in 40 view, the invention consists in the details of construction, and in the arrangement and combination of parts to be hereinafter more fully set forth and claimed.

In describing the invention in detail, reference will be had to the accompanying drawings forming part of this application where- 45 in like characters denote corresponding parts in the several views, and in which—

Figure 1 illustrates a view in elevation showing a device embodying the invention applied to the motor and interior of an auto- 50 mobile body;

Figure 2 illustrates an enlarged detail view showing the device applied to an intake manifold;

Figure 3 illustrates a view in elevation,

partly in section, of the device shown in Fig. 55 2, on an enlarged scale;

Figure 4 illustrates a view in elevation of an exhaust manifold and pipes as a modified auxiliary heater;

Figure 5 illustrates a sectional view of the 60 casing showing an auxiliary fuel burner for heating the interior of the casing; and

Figure 6 illustrates a similar view of the 65 casing having a modified auxiliary heating device.

In these drawings, 5 denotes an internal combustion motor having an intake manifold 6 connected to a suitable carburetor 7, which parts may be of any appropriate type and are not described in detail.

A casing 8, in this embodiment of the invention forms a heating chamber in which an electric heater 9 may be located, and the said heater may be supplied with current from a suitable battery 10 and from a generator, (not shown), such as is employed in association with automobile motors of conventional types. The casing is in communication with the intake manifold through a pipe 11 whose threaded nipple 12 is secured 70 in the intake manifold. The pipe 11 may be controlled by a valve 13 of the butterfly type, operative to establish or interrupt communication between the casing and the intake manifold so that a greater or less 75 amount of heated air may be supplied to the intake manifold for the purposes heretofore stated. The casing also communicates with branch pipes 14 and 15, the former of 80 which has a conduit or pipe 16 connected to 85 it leading to a register 18 and supplied with a valve 19 of any appropriate type, similar to the valve 13. The pipe 16 also has a coupling 20 to which a conduit or pipe 21 is 90 connected and the said pipe 21 may lead to 95 the interior of an automobile through a register 22, and the said pipe 21 may be provided with a valve 23 whereby passage through the pipe may be regulated.

The pipe 15 has a conduit or extension 24 leading to the interior of the crank case 25 for the purpose of supplying air to the crank case in a heated state for raising the 100 temperature of the interior of the motor in winter, and under pressure to effect its circulation through the interior of the motor for cooling the interior of the motor in summer the breather pipe 25 can be relied upon

ver of the first class 27. The lever 27 is pivoted at 28 between forks 29 provided at the extreme outer end of the main lever 7. The block 15 is provided with an extension 30 carrying a pin 31 engaging a slot in the lower arm of the lever 27.

As best shown in Figure 3, the lever 27 is normally so positioned that its upper arm extends outwardly. It follows that when the block 15 moves outwardly the point 32 will move not only inwardly, but also upwardly, and conversely, when the block 15 moves inwardly the point 32 will move outwardly and downwardly. It is this vertical component of movement which gives the desired zero correction for the scale.

As best shown in Figures 2 and 3, the spring 24 extends upwardly between the portions 14 of the main lever. The dash pot 33 of the scale is also located between these extensions. The piston rod 34 of the dash-pot is connected to a yoke 35 which is pivoted to the extensions 14 at 36. The yokes 35 and 20 are connected at their upper ends by a link 37. This construction is found in operation to provide a freely working dash-pot at all times. The piston rod 34 does not extend through a tight packing, but extends through an opening 38 in the top of the dash-pot, which opening is materially larger than the piston rod 34.

I have illustrated and described the present preferred embodiment of my invention, but it will be understood that it is not limited to this form alone, as it may be otherwise embodied within the scope of the following claims.

I claim:—

1. A scale comprising a lever, a member movable therealong, a load spring connected to the member and having its point of connection movable therewith, a load indicating means operatively connected to the lever, and means for shifting the point of connection of the load indicating means to the lever in a reverse direction to the direction of movement of the first mentioned member.

2. A scale comprising a lever, a member movable therealong, a load spring connected to the member and having its point of connection movable therewith, a lever of the first class pivoted to the first mentioned lever, one arm of said first class lever being connected to the member, and indicating means connected to the other arm.

3. A scale comprising a lever, a member movable therealong, a load spring connected to the member and having its point of connection movable therewith, a lever of the first class pivoted to the first mentioned lever, one arm of said first class lever being connected to the member, and indicating means connected to the other arm, the lever of the

first class being so positioned that the point of connection of the indicating means to the lever of the first class has an upward component of movement when the member is moved in one direction, and a downward component of movement when the member is moved in the opposite direction.

4. A scale comprising a lever, a member movable therealong, a load spring connected to the member and having its point of connection movable therewith, a lever of the first class pivoted on the first mentioned member, one arm of the lever of the first class being slotted, means on the movable member engaging the slot, and indicating means connected to the other arm of the lever of the first class.

5. A scale comprising a lever, a member movable therealong, a load spring connected to the member and having its point of connection movable therewith, a load indicating means operatively connected to the lever, means for shifting the point of connection of the load indicating means to the lever in a reverse direction to the direction of movement of the first mentioned member, and temperature responsive means for moving the member along the lever.

6. A scale comprising a lever, a member movable therealong, a load spring connected to the member and having its point of connection movable therewith, a lever of the first class pivoted to the first mentioned lever, one arm of said first class lever being connected to the member, indicating means connected to the other arm, and temperature responsive means for moving the member along the lever.

7. A scale comprising a main lever, a member movable therealong, a load spring connected to the member, indicating means, a rack bar for operating the same, and means for moving the point of connection of the rack bar with the lever in a reverse direction to the direction of movement of the movable member.

8. A scale comprising a lever, a load spring, a dash-pot having a piston rod, a yoke connecting the lever to the load spring, a yoke connecting the dash-pot piston rod to the lever, and a link connecting said yokes.

9. A scale comprising a lever having spaced apart portions, a load spring arranged between such portions, a dash-pot arranged between said portions, a yoke engaging the spring and making operative connection with the spaced apart portions, a yoke pivoted to the dash-pot mechanism and operatively connected to the spaced apart portions, and a link connecting the yokes.

In testimony whereof I have hereunto set my hand.

HOMER KENNEDY.

We claim:

1. A heater for auxiliary air of internal combustion motors comprising a casing having a connection with an intake manifold, a connection with the interior of a crank case and a connection with a heating register, a conduit extending through the casing and adapted to be connected to the exhaust manifold of an internal combustion motor, where-
5 by the radiation from the exhaust heats air delivered to the intake manifold, and a primary heating element in the said casing operative to initially heat air delivered to the intake manifold prior to the heating of said air from the exhaust of said motor, as and for the purpose described.
2. A heater for auxiliary air of internal combustion motors comprising a casing having a connection with an intake manifold, a connection with the interior of a crank case
10
- 15
- 20

and a connection with a heating register, a conduit extending through the casing and delivered to the intake manifold, a primary heating element in the said casing operated by the radiation from the exhaust heats air delivered to the intake manifold, a primary heating element in the said casing operative to initially heat air delivered to the intake manifold prior to the heating of said air from the exhaust of said motor, means for forcing air through the primary heating element to a part of an internal combustion motor communicating with the interior of said motor, and means for controlling the circulation of heat through the respective connections, as and for the purpose described.

ALBERT H. ALLERHEILIGEN.
